UNITED STATES PATENT OFFICE.

HENRY E. REEVE, OF NEW YORK, N. Y.

ELECTRIC BELL.

1,086,083.

Specification of Letters Patent.

Patented Feb. 3, 1914.

Application filed February 12, 1910. Serial No. 543,615.

To all whom it may concern:

Be it known that I, HENRY E. REEVE, a citizen of the United States, residing at New York, in the county of Kings and State 5 of New York, have invented certain new and useful Improvements in Electric Bells, of which the following is a specification.

My invention relates particularly to what is commonly known as vibrator bells or 10 gongs.

The principal objects are to permit an easy adjustment of the bell so as to vary the effective stroke of the hammer or striker and also to reduce the liability of the parts 15 working loose or becoming disengaged through ordinary use.

Figure 1, is a front view of apparatus embodying the improvements of my invention. Fig. 2, is a cross sectional view of the bell 20 and its support on the plane of the line X X of Fig. 1. Fig. 3, is a perspective view of the support and adjusting device for the bell, the parts being separated.

In the form that I have shown in Fig. 1, 25 the box or casing or frame 8 laterally encloses a horse-shoe electro-magnet 2 and its pivoted armature 3. The striker 4 projects from the casing in proximity to the bell or gong 5 which is carried by the supporting 30 bracket or extension 6 of the casing. A spring such as 7 may be employed when desired to oppose the action of the electro-magnet. The contact spring 8 and the contact screw 9 normally engaged thereby are 35 in the circuit with the coils of the magnet as is customary. The armature 3 may have a yielding spring or extension 10 for engaging the contact spring 8. The wire connector 100 is clamped by nut 103 to the piece 40 101 and is positioned in a notch, passage or recess in the upturned portion 102 to prevent it from turning. The other terminal may be the same. The contact screw 9 is carried by a bracket 19 and frictionally 45 held by a spring 20.

When the internal mechanism of the apparatus is properly adjusted it is often found that the striker or hammer is too close to or too far from the bell itself. For 50 the purpose of correcting this I have provided means for adjusting the bell to and from the striker without affecting the rest of the apparatus and without rotating the bell itself. The bell has a central passage 55 as is customary and also has a projection or pin 23 which extends into a recess or slot

24 in the upright or support 6. This prevents the bell from rotating relative to the support but does permit it to be moved somewhat toward and from the striker or hammer. Obviously the location of the pin and slot might be interchanged, the pin being on the support and the slot in the bell. The circular boss 25 has a passage 26 located eccentrically of its axis so that the boss is 60 in fact a cam and it fits into the usual central opening or passage in the bell. A screw 27 passes freely through this cam 25 and screws into the support 6. Integral with or securely attached to the cam 25 I have 65 provided the operating arm 28 which is slotted as at 29 to receive the tip of a screwdriver blade or other similar instrument. When the screw 27 is somewhat loosened a screw-driver may be inserted in slot 29 and the arm 28 and cam 25 then rotated in one direction or the other so as to cause the bell to be moved toward or from the striker 70 4. As the bell is not rotatable the tendency of the adjustment to work loose and shift 75 is reduced to a minimum. Where the adjustment is made by means of a hole in the bell off center the considerable leverage at the bell edge renders easy an accidental shift of adjustment. This I avoid. Preferably 80 the central opening in the bell is undercut and the adjusting member 25 is enlarged at the edge 52 so that when the screw 27 is removed the member 25 will not fall out and 85 get lost. The arm 28 serves as a sort of 90 washer so that when the screw 27 is tightened it clamps the gong against the top of the support or post 6.

What I claim is:—

1. In an electric bell construction, a support, a bell mounted on the support and held against rotation thereon, a cam rotatably mounted on the support and engaging the bell to effect a lateral adjustment of the bell as said cam is rotated, and means for 95 clamping the bell in adjusted position upon the support.

2. In a bell construction, a support having a threaded recess, a bell having a substantially circular opening, means for preventing rotation of said bell, a cam fitting in said opening and having a passage eccentric to its axis, a screw passing through said cam and taking into the threaded recess in said support.

3. In a bell construction, a support having a threaded recess, a bell having a substan-

tially circular opening, means for preventing rotation of said bell, a cam fitting in said opening and having a passage eccentric to its axis, a screw passing through said cam and taking into the threaded recess in said support and an operating arm for rotating said cam.

4. In a bell construction, a recessed support, a bell having an opening, a cam fitting in said opening and having an eccentric passage, a slotted operating arm for said cam and a locking member passing through said passage into the recess in said support.

5. In a bell construction, a support having a central recess and an elongated slot radial thereto, a bell having a central opening and a projection adjacent thereto guided in said slot, an eccentrically operated cam

in said bell opening and a pivot member passing through said cam and into said support.

6. In an electric bell construction, a support, a vibrating striker, a laterally adjustable non-rotatable bell on said support and having a central circular opening, a boss rotatable in said opening and having a passage eccentric to the opening in the bell, and a screw passing through said passage and screwed into said support and serving when loose as a pivot for said boss and when tight to clamp said boss and bell.

HENRY E. REEVE.
